3 Claims. (Cl. 148—9)

1

This invention relates to the thermochemical removal of metal from readily combustible ferrous metal bodies as by cutting, flame machining, boring, deseaming, desurfacing and similar operations. More particularly it relates to an improved method for rapidly initiating a thermochemical reaction between a jet of oxygen and a ferrous metal body which is readily amenable to ordinary thermochemical metal-removing procedures wherein only a jet of oxygen and a preheating flame are progressively applied against initial and successive portions thereof.

In the art of thermochemically removing metal from readily oxidizable ferrous metal bodies, such as carbon steel slabs, bars, billets, or blooms, a heating flame is directed against a portion of the surface to raise the metal to its oxygen ignition temperature. After a suitable time delay a stream of oxygen is directed against the heated portion of the surface to oxidize the heated ferrous metal, forming a molten mixture of iron oxide and metal which is driven out of the reaction zone by the force of the oxygen stream. The heating flame and oxidizing gas stream thereupon are moved relatively to the body along a path suitable for extending the metal removal operation in a desired direction.

When heating flames alone are used to heat a portion of a ferrous metal body for initiating a thermochemical metal removing operation, a substantial time interval elapses before the ignition temperature is reached. When such a metal removing operation is to be initiated on a round bar having no sharp edges, or within the boundaries of a cold metal body, it is an especially slow procedure to heat the metal to its ignition temperature, and undesirable gouging of the surface often occurs. Such gouging occurs even on hot steel if the movement of the blowpipe and the opening of the cutting oxygen valve are not so synchronized as to prevent it. As an illustration, the preheating time for starting a desurfacing operation at a square cut edge of a billet, using multiple nozzles, generally varies from 12 to 30 seconds for a cold steel billet and from 3 to 8 seconds for a hot steel billet. In an effort to decrease the preheating time there have been used heating flames of greater size and heating intensity than are normally required to maintain the metal removing reaction after its initiation, but this increases the operating cost with only a slight decrease in starting time.

Likewise, in the severing of a steel body such as a billet, bar, or slab, it has been necessary to pause at the edge of the body to preheat the edge

2

to its ignition temperature. This has been especially annoying when performing cutting operations on a large scale with a plurality of such steel bodies arranged side by side because preheating time must be lost at the edge of each successive body. One procedure has been to employ two operators, one for cutting and the other to preheat the edges in advance of the cutting operation.

In another procedure of the prior art for increasing the speed of starting a thermochemical reaction on a ferrous metal body, a short length of iron rod is positioned in front of the preheating flame and, when this length of rod has been raised to its ignition temperature, cutting oxygen is directed against the heated portion to ignite it. The burning portion of rod is blown against the surface of the body and the latter is thereby heated to its oxygen ignition temperature sufficiently rapidly that the cutting oxygen stream soon begins to attack the metal body. Once the metal removing action has been initiated, it proceeds normally without the addition of more iron rod, while relative movement is effected between the oxygen stream and the body.

While the starting rod method for initiating a thermochemical metal removing reaction has proved to be an important advance in the art, it has several disadvantages which are avoided by the method of the present invention. The feeding of a starting rod involves skillful coordination of the movements of the blowpipe operator for success in starting the removal of the metal. If insufficient time for preheating is allowed, the iron rod may not be up to the ignition temperature when the oxygen flow is started; or if too much time is allowed, the heated end of the iron rod may melt, fall off, and be blown away before the cutting oxygen flow is started. In either case there is a failure to initiate the metal removing operation. Also important is the fact that a delay of several seconds is required to bring the end of the starting rod to its ignition temperature before the oxygen flow can be started, so that running starts cannot be effected. Another disadvantage of the starting rod method is the need for a mechanical rod feeding device mounted in close proximity to the blowpipe nozzle for guiding the rod into the preheating flame. Such a device is exposed to damage, and sometimes complicates or prevents entirely the insertion of a blowpipe nozzle into a confined space. Moreover, in multiple nozzle work, such as desurfacing or multiple cutting, starting rods are not entirely dependable because it is not always possible to heat each rod to the ignition temperature in ex-

actly the same interval of time; and if too little or too much time elapses for preheating a particular rod it becomes impossible to initiate the oxidizing action of the oxygen stream from the corresponding nozzle. Another disadvantage of the starting rod procedure is that it cannot be effectively applied to nonhorizontal surfaces such as the side or bottom surfaces of ferrous metal bodies because the force of gravity tends to cause the preheated and ignited portion of the rod either to flow away from the reaction region or to drop away entirely from the surface.

Therefore, among the important objects of this invention are to provide a novel method for starting the thermochemical reaction of a jet of oxygen with a readily oxidizable ferrous metal body more rapidly than has heretofore been possible; and to provide such a starting method which is dependable and simple. Other objects are to provide such a method which can be used to start rapidly a thermochemical reaction on both horizontal and non-horizontal surfaces such as the top, side, and bottom surfaces of a ferrous metal body; which makes it possible to effect running starts in cutting, flame machining, desurfacing and like procedures; which can be used in confined locations; which is dependable for starting multiple nozzle metal removing operations such as desurfacing; and which permits the employment of a simplified mechanical construction, having but few moving parts to get out of order. Another object is to provide a novel method whereby a single operator can cut continuously across a plurality of ferrous metal bodies arranged side by side without pausing to preheat the edge of each successive body.

The above and other objects, and the novel features of the invention, will become apparent from the following detailed description having reference to the accompanying drawings, wherein:

Fig. 1 is a schematic side elevational view of one form of apparatus for performing the method of the invention, shown in position for cutting across a steel billet;

Fig. 2 is an enlarged vertical mid-sectional view of a part of the apparatus of Fig. 1 showing a cutting nozzle in position for cutting a kerf in a ferrous metal body;

Fig. 3 is an end view of the cutting nozzle shown in Fig. 2;

Fig. 4 is an end view of a modified form of cutting nozzle;

Fig. 5 is a side elevational view of a part of a modified form of apparatus for cutting ferrous metal by the method of the invention;

Fig. 6 is a bottom end view of the apparatus shown in Fig. 5;

Fig. 7 is a side elevational view showing a modified arrangement of the apparatus of Fig. 5;

Fig. 8 is a vertical mid-sectional view of the front end of one type of descaling or flame machining blowpipe properly positioned for descaling a ferrous metal body;

Fig. 9 is a side elevational view showing a motor-propelled carriage carrying a blowpipe in the proper position for cutting a series of juxtaposed billets by the method of the invention;

Fig. 10 is a cross-sectional view through a billet which has been nicked by the method of the invention for subsequent breaking by impact;

Fig. 11 is a side elevational view showing a blowpipe properly positioned for boring a hole

or center in the end of a steel billet by the method of the invention.

Briefly, my improved method of thermochemically removing metal from a readily oxidizable ferrous metal body such as carbon steel or low alloy steel, as by cutting, flame machining, descaling, desurfacing, or boring, comprises applying combustible adjuvant powder within a region on the body where the operation is to begin, heating the powder to its oxygen ignition temperature in a flame, and igniting and burning the powder by directing a jet of oxygen against both the body and the applied powder within such region, to propagate the heat of combustion of the powder to the body. A portion of the ferrous metal body in the starting region is in this way promptly raised to its oxygen ignition temperature and is ignited in the flowing stream of oxygen. After ignition of the body the application of powder is stopped and the flame and the flowing oxygen jet are advanced rapidly over a selected path relatively to the ferrous metal body, thereby oxidizing successive portions of the body. As in ordinary thermochemical metal removing operations, a fluid mixture of oxide slag and molten metal forms and is displaced by the kinetic energy of the oxygen stream.

The adjuvant powder can be introduced into the region of the oxidizing reaction in any suitable manner, but I have found it advantageous to entrain the powder in a gas, such as compressed air, and to direct the powder laden gas stream into the cutting oxygen jet which blows it against the ferrous metal body at the exact locality of oxygen impingement so that the heat of powder combustion is liberated almost exclusively in the starting region. Another suitable procedure for introducing the powdered adjuvant material is to suspend it in the metal removing oxygen stream before discharge from the blowpipe nozzle.

The adjuvant or "helping" powder ordinarily used to perform the method described above, desirably comprises a highly combustible metal such as powdered iron, low carbon steel, cast iron, or ferromanganese, and mixtures of such metals with one another and with other materials, such as aluminum or manganese. Adjuvant powders comprising about 80% steel and 20% ferromanganese or 80% steel and 20% aluminum are well suited for my novel method. It is to be understood, however, that my invention is not limited to the use of these specific metal powders nor even to metal powders as a class, since other combustible powdered materials can be used successfully for performing the method. Therefore, the term "adjuvant material" is used herein to denote any suitable combustible powder which permits an increase in the rate of starting thermochemical metal removal by my novel method.

More specifically, in rapidly cutting a deep narrow kerf along a selected path or cutting line on a readily oxidizable ferrous metal body by the method of my invention, a jet of oxygen, a stream of combustible metal powder, and a preheating medium such as an oxy-acetylene flame having sufficient heating intensity to heat at least the powder to its oxygen ignition temperature, are directed concurrently against the region of the surface where the cut is to be started. The powder quickly ignites and propagates its heat of combustion to the metal body, raising a portion of the body to its ignition temperature. In order to carry the combustion of the body to a

suitable depth, usually completely through the body, the oxygen jet is so directed as to penetrate deeply into the body, for example at an angle of 90° to the surface or at some other somewhat smaller angle. Once the oxidizing reaction has started the powder flow is shut off and the preheating medium and the jet of oxygen are advanced in unison relatively to the body in a direction substantially parallel to the surface along the desired path of cut, to ignite and burn successive portions of the body along the cutting line, leaving a deep kerf.

Most cuts are carried completely through the ferrous metal body with the object of severing the two portions on opposite sides of the kerf. However, by moving the jet of oxygen and the preheat medium so rapidly relatively to the body that the oxygen jet penetrates only partly through its thickness, heavy steel billets can be nicked at high speed as in Fig. 10 for subsequent impact breaking.

In the flame machining of a readily oxidizable ferrous metal body by the method of my invention, the reaction is initiated by concurrently directing against a region on the surface of the body from a suitable source a jet of oxygen flowing obliquely relatively to the surface in the direction of the path, a preheating medium such as an oxy-acetylene flame, and a stream of combustible adjuvant powder. As in cutting, the burning adjuvant powder propagates its heat of combustion to the base metal to ignite the latter, the powder flow is interrupted and the jet of oxygen and the preheating medium are advanced in unison relatively to the body along the selected path in a direction substantially parallel to the surface to ignite and remove successive portions of the body to a shallow depth. The jet of oxygen should be flowing with sufficient velocity and should be inclined at a small enough angle to the surface that the molten metal and oxide slag are blown forward along the selected path to assist in preheating successive portions of the metal. This procedure can be carried out with only a single nozzle as when deseaming a billet, or a bank of nozzles can be arranged side by side to remove a shallow layer from part or all of the surface of a billet, bloom, or slab.

My novel method for thermochemically removing metal from readily oxidizable ferrous metal bodies by using a powdered adjuvant material to initiate the reaction, as described in detail above, involves an extremely rapid initiation of the thermochemical reaction, far more rapid than has been possible heretofore. For example, in flame cutting a readily oxidizable ferrous metal body the cut can be started without any pause for preheating, by moving the cutting blowpipe toward the body at full running speed with the preheating gas burning, and the cutting oxygen jet and powdered adjuvant material flowing. Alternatively, a cutting blowpipe can be positioned above the exact point on the body at which the cut is to be initiated with the preheat gas burning and the cutting oxygen flowing, and by promptly thereafter applying a burst of powdered adjuvant material to the metal surface the cut is initiated instantly and relative movement between the body and the blowpipe can be started simultaneously with the application of powder. Such instantaneous starts are possible regardless of the shape or type of surface, so that bodies having round surfaces can be cut as expeditiously as those having sharp corners. My

starting procedure is a big improvement over both ordinary oxy-acetylene cutting, wherein preheating to the ignition temperature is accomplished solely by the oxy-acetylene flame, and over the starts obtained with a starting rod which must be preheated for several seconds before the cutting operation is actually initiated.

In cutting and deseaming, a burst of powder causes the metal removing operation to start immediately even if the starting point is within the boundaries of the metal body or is on a rounded surface having no sharp corners. In a desurfacing operation using my starting method, metal removal from a cold steel billet can be started in about $\frac{1}{10}$ to 2 seconds elapsed time with nine blowpipe nozzles arranged side by side and a powder flow between $\frac{3}{4}$ and 2 lbs./min., whether the start is made at a square cut edge or within the boundaries of the billet. In contrast, if powder is not used the starting time varies from about 10 seconds in the case of a cold billet or slab having a square corner to 30 seconds or more if the start is made within the boundaries of the metal body. The cost of starting a multiple nozzle desurfacing operation is about $\frac{1}{2}$ the cost of starting such an operation without any auxiliary material. Even using steel starting rods, the starting time for initiating desurfacing is 6 or 7 seconds. Moreover, starting a thermochemical desurfacing operation with powdered adjuvant material is more dependable than methods employing a plurality of starting rods, because there is involved in heating the powder to its ignition temperature no variable time element, such as is encountered when iron rods are heated at different rates.

When using powder solely for making a running start in the cutting of a metal body which can subsequently be cut fast enough without powder, I provide a thermochemical cutting nozzle adapted to direct both a preheating flame and a cutting oxygen jet against successive regions on the surface of the body along a selected cutting line or path, and continuously advance the nozzle, the flame, and the cutting jet to the body from a point short of where the flame and the cutting jet first impinge against the body, and then along the cutting line. At the instant of initial impingement of the flame and cutting jet, and while maintaining the advance of the nozzle, I deliver only against the region of initial impingement a small quantity of powdered adjuvant material oxidizable by the cutting oxygen to supplement the heat applied by the flame and substantially instantaneously heat the region of initial impingement to its ignition temperature, thereby avoiding interruption of the advance of the nozzle when starting the cutting operation. Thereafter the nozzle is advanced to cut the metal without the further introduction of powdered material.

Trials have indicated that running or instantaneous cutting starts can be made on rounds of various diameters and square cornered and rounded cornered blooms, billets, and slabs. Tests have also indicated that under most circumstances the speed of approach can equal the cutting speed. When powder is not used the time required for preheating prior to the starting of the cut will vary depending upon the shape of the material to be cut, being considerably longer in the case of a large diameter round than a small one and shortest for a relatively square cornered billet.

Also, if the cut is to be made within the boundaries of a plate or slab the preheat time required for the pierce at the beginning of the cut will be quite long without powder. These starting times may vary from 10 to 40 seconds depending upon the shape of the material and the position on the material where the start is to be made. When powder is used, however, the starting time can be reduced to not more than 1 or 2 seconds in the case of a start within the boundaries of the material. Tests have indicated that a powder flow rate of from 2 to 5 oz. per minute will produce a successful start.

In the thermochemical deseaming of hot steel bodies the practice has been to preheat with the flame for a period varying from 2 to 5 seconds. With my novel method, instantaneous starts are possible, and in multiple nozzle desurfacing flying starts can be made by positioning the nozzles off the end of the steel body, effecting relative movement between the nozzles and the body toward one another at a reduced rate with the heating flames, oxygen jets, and powder streams flowing, and increasing the speed of movement to a normal desurfacing speed after initiation of the thermochemical reaction. The established practice of preheating without powder has required that the steel body be held stationary during the preheat period.

My method provides several other advantages in addition to increased starting speed. The preheating flame need only be of the relatively small size and heating intensity needed for continuing the operation after its initiation, rather than the excessively large and hot flame ordinarily used. Such a starting procedure does not require such a skillful coordination of the operator's movements as is necessary when using a starting rod. Moreover, the initiation of a metal-removing operation is not limited to the horizontal top surface of a metal body, as is the case with a starting rod, but may be employed on the side and bottom surfaces as well.

In Figs. 1, 2 and 3 of the drawings, a cutting blowpipe 11 is shown in position for cutting a deep narrow kerf 13 in a square readily oxidizable steel billet 15 having rounded corners. Oxygen and acetylene are supplied to the blowpipe through the hoses 17 and 19 controlled by the valves 21 and 23, respectively. A portion of the oxygen is mixed with the acetylene within the blowpipe, in a well-known manner, to form a combustible gas mixture which flows through the conduit 25 to the nozzle 27, from which it is discharged and burned to form a preheating flame. The balance of the oxygen is employed for the cutting action and flows to the nozzle 27 through a conduit 29 having a shutoff valve (not shown) controlled by a valve lever 31.

A powder dispenser 33 containing a supply of suitable combustible adjuvant powder, such as steel, iron or mixtures of steel with ferromanganese or aluminum, has a gas inlet 35 and an outlet 37 for powder laden gas connected to a long hose 39 for conducting the powder laden gas to the blowpipe 11. One suitable type of powder dispenser is shown in Patent 2,327,337 granted August 24, 1943, to C. J. Burch and W. G. Edwards. The powder laden gas then passes through the conduit 43 to the nozzle 27 and is discharged to aid the cutting operation. Flow of the powder laden gas through the conduit 43 is controlled by a valve 45 in the head 47 connected by a rod 49 to a thumb lever 51 on the handle of the blowpipe.

As shown in detail in Fig. 2, the nozzle 27 is similar to ordinary cutting nozzles in having a central cutting oxygen passage 53 and a plurality of preheat gas passages 55 with outlets arranged on an annular zone surrounding the central passage for providing a ring of preheating flames 56 around the central cutting oxygen jet 58. In addition, the nozzle 27 has a plurality of longitudinal powder passages 57 having inlets arranged in a ring of larger diameter than the ring of preheat passages 55 and outlets arranged in a ring of smaller diameter than the preheat ring between the latter and the outlet of the oxygen passage 53. Suitable gas-tight seats 59, 61, and 63 separate the three sets of passages 53, 55 and 57 from one another and the atmosphere, and permit each set of passages to communicate exclusively with the corresponding one of the supply conduits 29, 25 and 43, respectively, through suitable passages in the head 47.

In operating the blowpipe shown in Figs. 1, 2 and 3 the valves 21 and 23 are adjusted to provide a preheating gas mixture which, when ignited, will form flames 56 of sufficient heating intensity to heat at least the adjuvant powder to its oxygen ignition temperature. The preheating flames 56 are then directed against the edge of the billet 15 and the oxygen and powder control levers 31 and 51, respectively, are depressed by the operator while he holds the blowpipe at a large angle to the surface such that the oxygen jet 58 will penetrate deeply into the billet. The adjuvant powder streams 65 instantly ignite and burn in contact with the surface of the billet 15, thereby heating a small portion of the latter to its oxygen ignition temperature almost instantaneously and initiating combustion. Immediately thereafter the valve 45 is closed by releasing lever 51 to interrupt powder flow and the blowpipe 11 is moved across the billet 15 parallel to its top surface to advance the jet of oxygen and the preheat flames in unison, thereby igniting and burning successive portions of the body and leaving a kerf 13.

Fig. 4 shows the end of a modified nozzle 66 wherein only a single adjuvant powder outlet 67 is located between the central oxygen passage 69 and the preheat ring 68 in a position to lead or lag the cutting oxygen jet. It is apparent that the number of powder outlets may be varied at will in accordance with the particular purpose for which each nozzle is designed.

Figs. 5 and 6 show an ordinary cutting nozzle 71, of well known construction, used in conjunction with a separate adjuvant powder supply nozzle 73. The lower portion of the powder nozzle 73 is inclined toward the nozzle 71 and has its outlet closely adjacent the lower end of the latter in position for discharging the stream of powder 75 between two of the preheat orifices 77 at a sufficient velocity to penetrate the preheat flame envelope 78 and impinge against the central oxygen stream 79.

Fig. 8 shows a blowpipe nozzle 85 in position for flame machining a shallow groove 86 in the surface of a steel slab 87, as in scarfing or deseaming. The nozzle 85 is designed for projecting an externally mixed type of preheating flame 88 toward the slab 87 by mixing together just outside of the nozzle acetylene gas from a ring of passages 89 and oxygen from the central passage 91. Powdered adjuvant material is introduced into the central passage 91 through ports 93 in communication with a supply passage 94 controlled by a valve 96. When starting a deseaming operation, the externally mixed type flame 88 is directed

obliquely against the surface of the slab 87 while the nozzle 85 is held at an acute angle thereto. Immediately thereafter, the cutting oxygen and adjuvant control levers (not shown) are depressed by the operator, thereby increasing the rate of flow of oxygen and causing the powder laden gas to flow through the powder inlet ports 93 into the passage 91. When the adjuvant powder impinges against the slab 87, it ignites and burns instantly, propagating its heat of combustion to the surface of the slab and heating the latter almost instantly to its oxygen ignition temperature to start the thermochemical reaction. Thereafter, powder flow is discontinued and the jet of oxygen and the preheating flame are advanced in unison relatively to the slab 87 substantially parallel to the surface along a selected path to ignite and remove successive portions of the billet to a shallow depth. Powder starting is especially advantageous for spot deseaming wherein the metal removing operation must be started within the boundaries of a steel body. Powder starting is also highly advantageous for flame machining a groove in the side edge of a plate to prepare it for welding to another plate, because the powder impinges against the plate directly. With a starting rod, the metal melted off by the flame tends to drop away under the influence of gravity. It is apparent that a nozzle designed for projecting premixed type flames toward the slab 87 can be used, if desired.

Fig. 9 shows a motor-propelled carriage 97 mounted upon a track 99 and carrying a machine cutting blowpipe 101 in proper position to cut a kerf 102 along a cutting line extending transversely across each of a plurality of elongated readily oxidizable ferrous metal bars or billets 108, 110, and 112 arranged side by side with their top surfaces in substantially the same plane. The incoming acetylene and oxygen streams for the heating flame are controlled by the two valves 103 and 105, the cutting oxygen stream by the valve 107, and the adjuvant powder flow by the valve 109. A nozzle 111 identical with that shown in Fig. 2 is attached to the lower end of the blowpipe for directing a heating flame and a cutting oxygen jet against successive regions on the surfaces of the bodies. When starting a cut with this cutting machine, the blowpipe 101 is usually positioned with the nozzle 111 spaced a small distance from the edge of the billet 108 at a point short of where the flame and oxygen jet initially impinge against one of the two outside bodies 108 and 112, with the preheat gases burning and the cutting oxygen jet and powder stream flowing. The cutting machine 97 is then started and advances continuously at full running speed (or some lower or higher speed) toward the billet 108 and, at the instant when the nozzle reaches the edge of the billet 108 the burning adjuvant powder and the flame cause the edge to ignite and the cut to start, no pause in the movement of the cutting machine being necessary. Powder flow is discontinued when the cut has started.

When cutting a series of bodies 108, 110, and 112 as shown in Fig. 9 by employing adjuvant powder only for increasing the starting speed, it is an important feature of this invention to deliver adjuvant material to the region of initial impingement of the heating flame and cutting oxygen jet against each succeeding body while continuing the advance of the nozzle without interruption along the several cutting lines in succession. By this procedure, I avoid interrupting the advance of the nozzle when starting the

cutting operation on the outside body, and when starting the cutting operation on each of the succeeding bodies of the side by side arrangement. In the arrangement shown in Fig. 9, for example, powder is delivered momentarily to the regions of initial impingement of the heating flame and oxygen jet against the initial edges of the steel billets 108, 110, and 112 in succession, but the powder flow is discontinued immediately after the thermochemical action begins at the initial edge of each billet so that the major portion of the kerf in each billet is cut without benefit of adjuvant powder. This procedure can be carried out on bars, billets, slabs, and like bodies of various shapes, such as round, square, or rectangular.

Running starts in flame machining and desurfacing operations can be accomplished with a procedure similar to that described above for cutting, using an appropriate propelling device.

Fig. 11 shows a blowpipe 113 positioned with its nozzle 115 close to the end of a billet 116 in which a hole 118 is being bored. Shallow holes can be drilled with the nozzle stationary, but deeper holes sometimes require movement of the nozzle along the axis of the oxygen stream. A blowpipe identical with that shown in Figs. 1 and 2 can be used for this purpose, and the powdered adjuvant material is discontinued after ignition of the billet metal has started.

Specific examples of the method of the invention have been described herein by way of example only. It is to be understood that changes in the method can be made within the scope of the invention, as defined in the claims appended hereto.

What is claimed is:

1. A method of rapidly initiating and effecting a thermochemical metal-removing reaction along a selected path on a ferrous metal body which is readily amenable to ordinary thermochemical metal-removing procedures wherein only a jet of oxygen and a preheating flame are progressively applied against initial and successive portions of said metal body, said method comprising first heating to its oxygen-ignition temperature a selected region of said body at which said metal-removing reaction is to begin by concurrently directing together against said region a jet of metal-removing oxygen, a preheating flame, and finely-divided burning combustible metallic adjuvant powder to cause said powder to impart its heat of combustion to said region whereby said body is heated substantially instantaneously to the oxygen-ignition temperature thereof in said region; then interrupting the supply of adjuvant powder to said region immediately after said body has become ignited therein; and thereafter continuing the thermochemical metal-removing reaction by directing only said jet of metal-removing oxygen and said preheating flame against successive portions of said body along said path in a direction away from said region.

2. A method in accordance with claim 1 which also comprises continuously advancing said preheating flame and said oxygen jet to said body and then along said path without interruption from a point short of where said flame and jet first impinge against said body; and, at the instant of initial impingement of said flame and jet against said body, blowing said burning finely-divided combustible metallic adjuvant powder against the region of such initial impingement.

3. A method in accordance with claim 2 wherein said adjuvant powder is advanced as a flowing stream together with said preheating flame

11

and said oxygen jet from a point short of where said flame and jet first impinge against said body.
